UNITED STATES PATENT OFFICE.

SOREN C. ROCKMAN, OF PHILADELPHIA, PENNSYLVANIA.

COMBINED COAL AND GAS RANGE.

1,244,246.

Specification of Letters Patent. Patented Oct. 23, 1917.

Original application filed September 17, 1914, Serial No. 862,137. Divided and this application filed May 6, 1915. Serial No. 26,193.

To all whom it may concern:

Be it known that I, SOREN C. ROCKMAN, a citizen of the United States, residing at Philadelphia, in the county of Philadelphia, 5 State of Pennsylvania, have invented certain new and useful Improvements in Combined Coal and Gas Ranges, of which the following is a specification.

The subject-matter of invention described 10 in this application is taken from or is a division of the application filed by me September 17th, 1914, Serial No. 862,137 for combined coal and gas ranges, Patent No. 1,155,758.

15 My invention relates to coal and gas ranges and it comprises a construction in which means are provided for using or employing either coal or gas as a heating fuel at different times or both at the same time.

20 One of the objects of my invention is to provide a construction comprising a top plate which is provided with an extension adjacent to one side of the range or stove which extension extends forwardly or front- 25 wardly in a direction substantially at right angles to the front of the range or stove. Said extension is provided with a hole or opening adapted to receive a pot or other cooking utensil and under the said hole or 30 opening a gas burner is situated which burner is in general horizontal alinement with other burners situated to the rear thereof in what may be termed the gas section of the range or stove.

35 Other objects and advantages of my invention will be specifically referred to and pointed out in the description of my invention which follows or will be apparent from such description.

40 In the drawings accompanying this specification and forming a part thereof I have illustrated one form of a convenient embodiment of my invention but it will be understood that changes in the details of construction may be made within the scope of 45 the claims without departing from my invention.

In the drawings:

Figure 1 is a view in front elevation of 50 a portion of a coal and gas range embodying my invention, showing a portion of the

front part of the stove broken away and certain parts thereof in section;

Fig. 2 is a view in side elevation of the range or stove shown in Fig. 1; and 55

Fig. 3 is a transverse sectional view taken on the line 3—3 of Fig. 1 and showing the top plate of the range or stove in plan.

Referring to the drawings, 1 designates the body portion of the range or stove including the oven 2 and fire-box 3, the former being preferably spaced from the outside walls of the body part of the range or stove to provide for the passage of products of combustion and the latter, that is the fire-box, suitably bounded on one side by the customary water-back 4. The oven 2 is also spaced from the top plate 5 of the range or stove forming a space between the oven and the said plate which is adapted to receive 70 the hot products of combustion from the fire box 3 and which is also provided with auxiliary gas burners 7, 7^a and 7^b. 65

On opposite sides of the burner 7 dampers or valves 8 and 9 are provided forming a chamber 6 in the space above the oven 2. The damper or valve 8 should be closed and the damper or valve 9 opened when it is desired to use the gas burner 7 for any purpose. At such time the products of combustion from the fire-box 3 are cut off from the chamber 6 as is clear from an inspection of Fig. 1 of the drawings. 75

When the burner 7 is being used the air which is necessary to the combustion of the gas issuing from such burner is supplied through the opening 10. When the burner 7 is not in use and heat is being employed from the fire-box only the valve or damper 9 should occupy a vertical position closing 80 the opening 10 while the valve or damper 8 should occupy a horizontal or a partially horizontal or open position to admit the heat freely from the fire box 3 into the chamber 6. 85

In order to prevent ashes, soot, etc., from collecting in the perforations of the burners 7, 7^a and 7^b I provide plates 10^a which rest upon the tops of said burners. These plates are provided with perforations (not shown) 100 and may slide or turn with respect to said burner so as to place said perforations 95

either in or out of registry or alinement with the perforations of the burners. To prevent accidental displacement or removal of the plates 10^a from the burners they are 5 provided with flanges 10^b which extend downwardly around said burners. To limit sliding or turning movement of said plates I provide the short slots 10^c in the respective flanges through which pins on the sides 10 of the burners project.

11 designates a gas burner located in the lower portion of the body part of the stove or range and positioned beneath the oven 2 so that the latter may be heated satisfactorily in case the gas burner is used instead 15 of a coal or other fuel burning fire-box.

The gas burner 11 receives its gas from the conduit 12 which is connected to the gas supply pipe 13 and is controlled by any 20 well known type of valve 14.

24 designates the flue which communicates at its lower end with the combustion chamber of the body part 1 of the range or stove and passes upwardly, conducting the 25 products of combustion to a suitable chimney or vent not shown.

A portion of the top plate of the stove or range is projected forwardly substantially at right angles to the front of the range as indicated at 60 to provide an extra opening 61 in the top of the range or stove. A permanent gas burner 62 of any suitable construction is provided underneath the opening 61 for furnishing the heat necessary 30 for cooking or similar purposes. Said burner 62 may be provided with a sliding or turning plate such as 10^a for preventing the ashes, etc., from entering and closing the perforations of the burner.

40 By extending the projection 60 forward beyond the front plane of the range or stove, as indicated in Fig. 3 of the drawing, I am enabled to secure greater capacity without, however, causing a stove to take up 45 or require any additional room in a lateral direction.

If the part 60 projected from the side instead of the front of the range or stove it will be understood that the range or stove 50 would take up more space along the wall of a room, assuming that it were positioned against the wall upon one side of the room as is usually the case, than when constructed as shown.

55 It is also usually the case that the available space along any one wall of a kitchen, and particularly in modern apartment houses, is very limited, so that the importance of increasing the capacity of the stove or range without at the same time increasing the lateral space occupied thereby is great.

In my construction the part 60 projects from the front of the range or stove above 60 the oven door 65 but does not in any way

interfere with the opening of such door or with the ready access to the oven nor does it interfere with the opening of the door 66 of the fire-box or chamber and the ready access to the same.

70 In opening and closing the oven door swings underneath the projection 60 and the burner 62.

I claim:—

1. In a combined coal and gas range, the 75 combination of a fire-box for burning fuel such as coal in one end of said range, an oven, a chamber at the other end of said range to receive the heated gas from the fire-box, a passage for said gases said passage extending over the oven, a valve supported above said oven for closing the passage to said chamber, gas burners situated in said chamber for use when said valve is in closed position, a protector for said 80 burners slidably mounted thereon for preventing ashes from entering the said burners when coal is used, a top plate for the said range said top plate having pot holes therein over the chamber within which is located 90 the said burner, and said top plate being provided with a projection at one end of the said range which projection extends beyond the front of the range and at right angles thereto and in alinement with the said pot 95 holes and said burners and the said projecting portion of the top plate having a pot hole therein, and a burner below the said pot holes, substantially as described.

2. In a combined coal and gas range, the 100 combination of a fire-box for burning fuel such as coal, a chamber to receive the heated gases from the fire-box, an oven, a valve situated above said oven for closing the passage-way from said fire-box to said chamber, the said range having an opening through a wall thereof for the passage of air into the said chamber, a valve for closing and opening said air passage-way, the latter valve being in opened position when 105 the first-named valve is in closed position, a gas burner within the said chamber and adapted to be used when the second-named valve is in open position, the first-named valve being in closed position at such time, 110 a movable protecting plate for said burner in said chamber, a top plate for the said range said plate having a forwardly extending projection in alinement with the said chamber, said projection having a pot 115 hole, a burner for burning gaseous fuel situated below the said pot hole in said projection, substantially as described.

3. In a kitchen range, a chamber for burning coal or similar fuel, an oven, a top cooking plate one end portion of which is over the said chamber such end portion being narrower than the opposite end portion of the said top plate, a passageway leading from said chamber underneath the said top 120 plate, a valve for closing the said passageway, a burner for burning gaseous fuel situated below the said top plate, a top 125 cooking plate having a frontwardly extending projection in alinement with the said chamber, said projection having a pot hole, a burner for burning gaseous fuel situated below the said pot hole in said projection, substantially as described.

plate and over the said oven to a heat chamber, a valve situated intermediate the top plate and the said oven said valve being adapted to open and close the said passage-way to said heat chamber, burners in the said chamber, an end plate for the range said end plate having air inlet passages through which the air may pass to said heat chamber, the said range including a flue extending 5 from said heat chamber downwardly between said end plate and said oven, a valve situated adjacent to said end plate and adapted to open and close the air inlet openings and also adapted to open and close 10 the said flue, the said top plate having pot holes for cooking by coal and also having pot holes for cooking by gas and the said top plate having a frontwardly extending projection said projection having one or 15 more pot holes therein and gas burners underneath the said pot holes in said projection, substantially as described.

4. In a kitchen range, a coal fire chamber, an oven, an end plate having an air 20 inlet opening said plate forming one wall 25 of a heat flue included within the said range,

a top cooking plate situated a distance above the said oven and forming one wall of a heat passage-way or flue over the said oven, a valve intermediate the said top plate and 30 said oven for closing said passage or flue, a valve supported adjacent to the said end plate for closing said air inlet opening and the first-named flue, said top cooking plate having pot holes for cooking by coal and 35 pot holes for cooking by gas, burners situated underneath the said last-mentioned holes and the said top cooking plate having a projection extending forwardly from the front plane of the stove at right angles to 40 said plane and in alinement with the said burners, said projection having one or more pot holes therein, and gas burners situated underneath the said pot holes.

In testimony that I claim the foregoing 45 as my invention, I have hereunto signed my name this 4th day of May, A. D. 1915.

SOREN C. ROCKMAN.
